[57] CLAIM

The ornamental design for a portable marine control unit, as shown and described.

DESCRIPTION

FIG. 1 is a front perspective view of a portable marine control unit showing my new design;
FIG. 2 is a front elevational view thereof;
FIG. 3 is a top plan view thereof;
FIG. 4 is a bottom plan view thereof;
FIG. 5 is a rear elevational view thereof; and,
FIG. 6 is a side elevational view thereof, the opposite side elevational view being a mirror image of that shown.

FIG. 1

FIG. 2

FIG. 3

FIG. 4

FIG. 5

FIG. 6
